189,659

TENT OR SIMILAR ARTICLE

Dorothy Spencer Bateman, 111 13th St., and William Joseph Holt, Jr., 1600 Melody Lane, both of Garland, Tex.

Filed Aug. 21, 1956, Ser. No. 42,678

Term of patent 3½ years

(Cl. D88—3)

FIG. 1

FIG. 2

FIG. 3

FIG. 5

FIG. 4

Fig. 1 is a front elevational view of a tent or similar article, showing our design, the back and lateral sides of this device being similar to the front view except with no opening therein;

Fig. 2 is a side elevational view showing the detachable side walls removed;

Fig. 3 is a side elevational view of the tent of Fig. 2 showing the top tilted;

Fig. 4 is a front elevational view of the device shown in Figs. 2 and 3, but in this instance in its stowed position; and

Fig. 5 is a top plan view thereof.

We claim:

The ornamental design for a tent or similar article, as shown and described.
